United States Patent Office

Des. 196,498
Patented Oct. 8, 1963

196,498

COMFORT STATION

William F. McClenahan, 778 Burlway Road,
Burlingame, Calif.

Filed Mar. 26, 1963, Ser. No. 74,141

Term of patent 14 years

(Cl. D13—1)

FIG-1

FIG-2

FIGURE 1 is a perspective view of one side of the new comfort station embodying my design.

FIGURE 2 is a perspective view of the opposite side of the comfort station.

The dominant features of my design reside in the portion shown in full lines.

I claim:

The ornamental design for a comfort station, as shown and described.
